FILING CASE

Percy F. Grand, Toronto, Ontario, Canada, assignor to Grand & Toy Limited, Toronto, Ontario, Canada

Application May 19, 1932. Serial No. 612,247

7 Claims. (Cl. 229—47)

The principal objects of this invention are to provide an improved form of fastening device for the closure flaps of storage file cases which may be easily applied, and to provide a form of fastening device which will co-operate with the closure flaps to reinforce and detachably lock the same securely together and prolong the effective life of the case.

The principal feature of the invention consists 10 in the novel construction and arrangement of parts whereby the adjacent edge portions of a pair of closure flaps are gripped between and held in closed relation to the case by a U-shaped fastening clip member pivotally attached to one 15 of the flaps to be swung into and out of locking relation with the closure flaps.

A further and important feature consists in the provision of channeled reinforcing elements fitting over the respective flap portions adjacent 20 to the locking member to be engaged thereby and to effect a local reinforcement of the flaps, the fastening member being pivotally secured to one of said reinforcing members.

In the drawing, Figure 1 is a perspective view 25 of a storage filing case showing my invention applied thereto and in a locked position.

Figure 2 is a perspective view showing the filing case open and the locking devices swung outwardly.

Figure 3 is a fragmentary perspective view of 30 one corner of the filing case showing the locking device before being swung inwardly to its locking position.

Figure 4 is a vertical mid-sectional view 35 through the fastening device showing the same in locked relation with the closure flaps.

Figure 5 is a perspective detail illustrating a modified form of the invention.

In the manufacture of storage filing cases it 40 is customary to provide some means for holding the cover flaps closed. The present invention provides a very efficient form of fastening means for this purpose.

In the form of the invention shown, the case 45 1, which may be formed in any well known manner, preferably from heavy corrugated stock, is here shown provided with closure members in the form of end flaps 2 and side flaps 3 and 4. Reinforcing corner pieces 4', which may be 50 formed either of thin metal or sheet fibre, are doubled intermediate of their width and placed over the respective end corners of the closure flap 3 so that they snugly embrace the same and form a positive reinforcement therefor.

55 Rivets 5 extend through the members 4' and

the embraced portions of the flap 3 and are suitably spaced inwardly from the end and side edges thereof.

The rivets 5 extend through the arms 6 of the U-shaped fastening clip members 7 so that the fastening members may be swung into and out of vertical alignment with the reinforcing members 4.

A reinforcing member 8 formed similarly to the members 4' of metal or fibre snugly embraces the end edge of the flap 4 so that when the flaps are swung closed as shown in Figure 3, with the flap 3 overlying the flap 4, the reinforcing members 8 will be positioned below the corner portions of the members 4'. 70

Rivets 9 or other suitable means secure the members 8 in position.

The gripping side members 10 of the fastening device 7 is preferably spaced substantially parallelly apart a distance somewhat less than the 75 combined thickness of the members 4' and 8 so that when these closely overlie each other and the fastening member 7 is swung inwardly, as shown in Figures 1 and 4, the members 4' and 8 and enclosed portions of the flaps 3 and 4 will 80 be firmly gripped between the side members 10, thus firmly holding the flaps in a securely locked position.

The smooth rounded edges 11 and 12 presented by the reinforcing members 4' and 8 85 respectively will effectively guide the advance portions of the side members 10 of the clip in moving the latter to the locking position and any wear of the movable fastening member against the flap is prevented by the presence of 90 the members 4' and 8, which effectively take up any local strain and distribute the same over an extended area.

As shown in Figure 3, corrugations 13 may be formed in the inner corner portion of the members 4' on the upper face thereof and corresponding corrugations 14 are shown formed in the upper side member 10 of the fastener 7 to register with the corrugations 13 when the fastener is swung to its closed position. The inter-engagement of the respective corrugated portions assisted by the natural resiliency of the U-shaped fastener effectively holds the fasteners in position against accidental displacement. 95

A lug extension 15 on the member 7 serves as 100 a finger grip to facilitate movement of the fastening members to or from their locked position.

It will be understood that many variations in the actual structure may be resorted to while still remaining within the scope of the invention and 110

in the modification shown in Figure 5 I show an arrangement in which the pivotal locking member is shown effecting a co-operative locking connection between the edge-abutting type of closure flap.

What I claim as my invention is:

1. A storage filing case having side flaps adapted to be turned inwardly one over the other to close the case, and clip members pivotally secured at the respective free corners of the overlying flap and having portions adapted to swing under the underlying flap to secure the overlying flap thereto, one of said flaps having protuberances forming a co-operative interlock with said pivotal slip members to lock the latter in their flap-locking position.
2. A storage filing case having longitudinal side flaps of a width substantially equal to the width of the case and adapted to be folded one over the other, and U-shaped clip members having an extension arm pivotally secured to the overlying flap at a point spaced inwardly from the side and end edges thereof and adapted to be swung inwardly to embrace the corner of the overlying flap and the underlying portion of the under flap to secure the same together, said U-shaped clip members having the intermediate loop portion extended longitudinally to form a free lug therebeyond to act as a finger grip.
3. A storage filing case having closure flaps, reinforcing plates embracing adjacent portions of said closure flaps when the latter are in their closed position, pivotal locking means engaging the respective reinforcing members of said flaps in pressure contact to hold the same in their closed position, and means for interlocking said pivotal locking means and plates to retain the same in pressure contact.

4. A storage filing case having longitudinal closure flaps of a width substantially equal to the width of the case and adapted to be turned inwardly one over the other to close the case, U-shaped reinforcing corner plates embracing the corners of the uppermost flap, clip members pivotally secured to said reinforcing corner plates at a spaced distance from the end thereof, and reinforcing plates embracing the end edges of the under flaps adjacent the point of connection with the case, said fastening clips being adapted to be swung into pressure locking contact with said reinforcing plates to lock the flaps closed.

5. A storage filing case having closure flaps, reinforcing corner pieces secured to one of said flaps, U-shaped fastening clips pivotally secured to said reinforcing corner pieces and adapted to embrace said corner pieces and the adjacent portions of the other flap, and means effecting an interlock between said corner pieces and said pivotal locking members to retain the latter against accidental displacement from their locking position.

6. A storage filing case as claimed in claim 5 in which said corner pieces and pivotal locking members are provided with inter-fitting corrugations to effect the interlock therebetween.

7. A storage filing case having closure flaps, reinforcing plates embracing adjacent portions of said closure flaps when the latter are in their closed position, and pivotal clip members movable into and out of clamping relation with the said flaps and plates, said plates presenting a wear-resisting surface on the respective flaps to prevent damage to or crushing of the material of the flaps in constantly moving the pivotal clips into and out of clamping relation thereto.
